(57) **CLAIM**

The ornamental design for a BUCKLE as shown and described.

DESCRIPTION

FIG. 1 is a front, left-side, bottom perspective view of a female half of the BUCKLE;

FIG. 2 is a front elevational view thereof;

FIG. 3 is a top plan view thereof;

FIG. 4 is a left-side elevational view thereof;

FIG. 5 is a right-side elevational view thereof;

FIG. 6 is a rear elevational view thereof;

FIG. 7 is a bottom plan view thereof;

FIG. 8 is a front, top perspective view thereof;

FIG. 9 is a front, right-side, bottom perspective view thereof;

FIG. 10 is a rear, left-side, bottom perspective view thereof;

FIG. 11 is a front, left-side, bottom perspective view of a male half of the BUCKLE;

FIG. 12 is a front elevational view thereof;

FIG. 13 is a top plan view thereof;

FIG. 14 is a right-side elevational view thereof, the left-side elevational view (not provided) being a mirror image thereof;

FIG. 15 is a rear elevational view thereof;

FIG. 16 is a bottom plan view thereof;

FIG. 17 is a rear, left-side, bottom perspective view thereof; and

FIG. 18 is a front elevational view of the female half and the male half in a mated configuration.

The broken lines depict environment and form no part of the claimed design.
